ATTORNEY.

UNITED STATES PATENT OFFICE.

EDWIN LICHTENSTEIN, (NOW BY JUDICIAL CHANGE OF NAME EDWIN LANE,) OF NEW YORK, N. Y.

COLLAR-SHAPER.

1,355,557.

Specification of Letters Patent. Patented Oct. 12, 1920.

Application filed October 16, 1917. Serial No. 196,836.

To all whom it may concern:

Be it known that I, EDWIN LICHTENSTEIN, citizen of the United States, residing at New York, in the county of New York and State of New York, have invented certain new and useful Improvements in Collar-Shapers, of which the following is a specification.

This invention relates to collar shapers or ironers, and more particularly to devices for shaping collars of the turn-down variety.

The object of the invention is to provide an improved device for shaping turn-down collars by the traveling movement of an ironing or shaping member along the folded edges of the collar, and which device is so arranged as to limit the amount of ironing pressure applied to the collar by the operator to a predetermined amount, putting it beyond the possibility of the operator cutting through or wearing the collar by unnecessary pressure, but nevertheless permitting the predetermined pressure to be adjusted to any desired amount and always insuring the use of pressure up to the full amount for which the device is set.

A further object of the invention is to provide simple apparatus of this kind which can be made and sold at low cost and can be readily manipulated by the operator.

Further objects of the invention are in part obvious and in part will appear more in detail as hereinafter set forth.

The invention comprises the collar shaper hereinafter described and claimed.

In the drawings, which represent one embodiment of the invention, Figure 1 is a plan view showing the ironing member in idle position, the form being arranged to receive the collar; Fig. 2 is in part a side elevation, and in part a cross section on the line 2-2 Fig. 1, showing the ironing member in operating engagement with the form; and Fig. 3 is a sectional elevation on the line 3-3 Fig. 1.

Referring to the drawings, 1 indicates a suitable support for the device, such as a table or the like, which is provided with an opening to receive the depending tubular portion 2 of a casing or jacket whose upper portion 3 rests upon the support 1 and is provided at one side with a small guiding opening 4 whose purpose will appear.

Within the tubular member 2 and slidably vertically therein is a tube or sleeve 5 depending from the spider-like base 6 of the ironing form, which is provided with a circumferentially extending upwardly projecting rim or wall 7, whose upper edge is designed to receive and support the fold of the collar to be shaped, and which at one side is provided with the usual gap or opening 8. The body 6 is also provided with a depending pin 9 entering and moving vertically in the guiding opening 4 and which opening permits the form to move vertically in the body but without rotation relative thereto.

10 represents the ironing member which may be a hollow casting of the usual form provided with an ironing recess 11 designed to coöperate with the upper edge of the form 7 and shape the collar. The ironing member is rotatable about the vertical axis of the tubes 2 and 5, which axis is concentric with the form 7. To rotate the ironing member it is provided with the usual operating handle 12. Member 10 has a sleeve portion 13 supported by the horizontal tube 14 and secured thereto by the screws 15, which also secure in place a horizontal extension 16 having a sleeve 17 upon the opposite closed end of tube 14, whose front end is open to discharge heated or burning gas into the ironing member 10 for heating the same, or which may serve as a conduit 85 for conducting lead wires to electrical heating units in said ironing member. Between the opposite ends of the pipe 14 is a hollow fitting 18 secured to the upper end of the tube 19, which passes down within the tube 5 and is provided below the lower end of the tubular member 2 with a collar 20 to prevent upward movement of the tube 19 and ironing member relative to the support. Surrounding the tube 19 is a spiral compression spring 21 resting at its lower end upon a collar 22 within the tube 2 and at its upper end bearing against the lower end of a sleeve 23 adjustably threaded into the base 6 and capable of being locked in adjusted position by the locking nut or ring 24. This sleeve 23 enables the pressure of the spring 21 to be varied for increasing or diminishing the predetermined ironing pressure.

Fitting 18 at one side is provided with a laterally extending projection 25 serving to support a roller or anti-friction member 26 which travels along the upper surface of a 5 circumferentially extending cam 27, having an inclined actuating portion 28, horizontally extending dwell 29 and a stop 30.

The lower end of the tube 2 also serves to support a bracket 31 to which is secured the 10 fuel supply pipe 32 for conducting liquid or gaseous fuel to the usual Bunsen mixer 33. The gas can burn at this mixer to produce a stream of heated products of combustion for heating the iron 10 or can burn at the 15 mouth of the pipe 14, as will be readily understood.

The collar to be shaped is applied to the upper edge of the form 7 when the parts are in the position shown in Fig. 1 with the 20 ironing member 10 at the gap 8. In this position the roller 26 rests upon the dwell and against the stop 30 of the cam and holds depressed, as in Fig. 3 the collar receiving form. When the collar is applied, the 25 ironing member 10 is swung around in a clockwise direction Fig. 1, as indicated by the dot and dash line, Fig. 1. During this movement the roller 26 travels to and along the inclined cam surface 28 thereby allowing 30 the collar holding form to rise to the full line position, Fig. 2, until it meets the ironing member 10, which prevents further upward movement of the collar holding form. During the further motion of the 35 ironing member around the vertical axis—the ironing motion—the ironing pressure is determined absolutely by the pressure of the spring 21 and can be neither increased nor diminished by the pressure the operator 40 applies to the handle 12. Consequently by properly adjusting the sleeve 23 to secure the desired and proper pressure the operator is prevented from injuring the collars worked upon and must always apply to 45 each collar the exact degree of pressure previously determined by the adjustment of the device.

What I claim is:—

1. A collar shaper, comprising an annular vertically movable collar holding form member, a coöperating ironing member, said form member and said ironing member being relatively rotatable, yielding means for moving said form member vertically into engagement with said ironing member, and means actuated by one of said members for withdrawing the other from ironing position.

2. A collar shaper, comprising an annular vertically movable collar holding form, a coöperating ironing member rotatable in a horizontal plane, yielding means for moving said form vertically into engagement with said ironing member, and means 60 whereby rotation of said ironing member 65

withdraws said form from the plane of movement of said ironing member.

3. A collar shaper, comprising an annular vertically movable collar holding form, a coöperating ironing member rotatable in a horizontal plane and having an idle position, yielding means for moving said form vertically into engagement with said ironing member, and coöperating means on said form and member whereby said member in 70 moving to idle position withdraws said form from the plane of movement of said ironing member in 75

4. A collar shaper, comprising an annular vertically movable collar holding form, a coöperating ironing member rotatable in a horizontal plane and having an idle position, yielding means for moving said form vertically into engagement with said ironing member, coöperating means on said 80 form and member whereby said member in moving to idle position withdraws said form from the plane of movement of said ironing member, and in moving away from idle position releases said ironing member for 85 movement thereof toward said ironing member.

5. A collar shaper comprising a collar form, an iron having an ironing portion guided for movement in a fixed path a portion of which is coincident with said form and another portion of which is beyond the same, means tending to yieldingly move said form into the path of said iron, and means carried by said iron for holding said form 95 depressed when said iron is moving above the form into ironing position.

6. A collar shaper comprising a collar form, an iron having an ironing portion guided for movement in a fixed path, a portion of which is coincident with said form and is the ironing range and another portion of which is beyond the form and is the idle range, means tending to yieldingly move said form into the path of said iron, and 105 means controlled by said iron for holding said form depressed when said iron is moving from idle range to ironing range.

7. A collar shaper comprising a manually operable ironing member supported 115 for movement in a curved path and held against movement out of said path, a movable collar holding form coöperating therewith, means tending to move said form toward said path, and coöperating parts on 120 said member and form for controlling the movement of said form.

8. A collar shaper comprising an ironing member having movement in a curved path and held against movement out of said 125 path, a collar holding form coöperating therewith, means for producing yielding vertical movement of said form, coöperating parts on said member and form controlling said vertical movement, and means for vary- 130

ing the yielding tendency of said vertical moving means.

9. A collar shaper comprising an ironing member movable in a fixed path and held against movement out of said path, a collar holding member coöperating therewith, means tending to yieldingly move said col-

lar holding member toward said path, a cam on one of said members and means carried by the other of said members and 10 engaging said cam for controlling the movement of said collar holding member.

In testimony whereof I affix my signature.

EDWIN LICHTENSTEIN.
